United States Patent Office

Des. 207,496
Patented Apr. 25, 1967

207,496

CAKE CONTAINER

James B. Swett, Barrington, R.I., assignor to Rexall Drug and Chemical Company, Los Angeles, Calif., a corporation of Delaware

Filed July 6, 1965, Ser. No. 86,041

Term of patent 14 years

(Cl. D44—1)

FIG. 1

FIG. 2

FIG. 3

FIG. 4

I claim:

The ornamental design for a cake container, substantially as shown.
